UNITED STATES PATENT OFFICE.

WRAY FALWELL, OF FITCHBURG, MASSACHUSETTS.

VALVE-OPERATING DEVICE.

Application filed September 9, 1924. Serial No. 736,798.

To all whom it may concern:

Be it known that I, WRAY FALWELL, a citizen of the United States, residing at Fitchburg, in the county of Worcester and State of Massachusetts, have invented a new and useful Valve-Operating Device, of which the following is a specification.

This invention relates to a device for use on the engine of a Ford car, particularly, although the same principles can be applied to other engines, for increasing the speed of opening and closing of the valves and thereby economizing greatly in the use of fuel, increasing mileage per gallon of gas, and improving the smoothness of operation.

One object of the invention is to provide a construction in which the parts for performing the quick operation of the valves will be mounted in a unit which is readily applicable to the engine without material modification of the parts which are now in place and which can be anchored in position very easily so that it cannot work loose and yet can be removed, if desired. The invention also involves a construction in which the pivoted levers do not have to be bored to pivot them and locate them in the proper place. In this way these levers can just be set in and they are so arranged and shaped so that they will not work loose nor get out of place, but will operate effectively.

An important feature of this invention consists in the provision of a wearing plate for receiving the wear from the levers of such a nature that it will not have any sliding action on the bottom of the valve stem and therefore the valve stem will not wear out at this point, thus overcoming an objection that has been encountered heretofore in connection with this particular type of device.

Other objects and advantages of the invention will appear hereinafter.

Reference is to be had to the accompanying drawings, in which

Fig. 1 is a longitudinal sectional view through the centers of a series of valves and stems of the engine of a Ford car showing a preferred embodiment of this invention applied thereto;

Fig. 2 is a sectional view on the line 2—2 of Fig. 1; and

Fig. 3 is a plan of the separate unit

adapted to be inserted in the engine and adapted to carry the elements of this invention.

I have shown the invention as applied to a type of engine well known, being used universally at the present time in Ford cars, and the exact construction of this invention as shown in the drawings is particularly adapted to that type of car. Yet the principle of the invention is capable of use with most internal combustion engines. In the drawing I have shown the usual valve stems 11 and valve lifters or plungers 12. Each valve stem is provided with a valve spring seat or washer 13, the motion of which is limited by a pin 14 through the valve stem. I have shown the usual valve cage 15 and valve stem guide 16, the valve cage being provided with the usual valve seats 17 on which the valve 18 secured to the valve stem is adapted to seat. Surrounding a portion of the valve stem guide 16 and seated in the spring seat or washer 13 is a helical spring 20 for holding the valve closed with a yielding pressure. As usual, the valve is operated through the stem 12 by a cam 21 on a cam shaft 22. The parts thus far described are, of course, duplicated for each valve and are common in this class of engines and I do not claim these features.

This invention in itself involves a casing 25 of sheet metal which is struck out so as to have the desired shape. This casing is rectangular in form and in the present case I have shown it in double form so that it is adapted to be used with two of the valve plungers 12. The casing is provided with a perforation for receiving a bolt 27 which passes through it and is held up against the valve case, being adjusted to press against it and securely hold the casing 25 in position against spacing washers 28 on the frame. Nuts 29 are used to receive the proper adjustment.

There are two holes in the bottom of the casing 25 for receiving the plungers 12. Instead of having the plungers engage the valve stems or instead of having them all in one piece, I cut one of them off so as to separate them from each other a distance substantially equal to the height of the casing.

The casing 25 is made with pairs of holes

through its opposite side walls and in these are placed pivot pins 30, four of them in the form shown. These pins are mounted a little above the bottom of the casing and are 5 intended to constitute the means for pivotally mounting four cam levers 31. Each of these cam levers is made with a semi-cylindrical depression 32 in the top and with a quadrant 33 centered at this depression and 10 constituting the tip end of the lever. The levers are put in place with the pins 30 in the depressions 32. The quadrant is provided to permit the lever to swing on its pivot and yet remain in contact with the bottom 15 surface of the casing so that it cannot become detached from the pivot pin. By this simple means I avoid the necessity of boring holes in cam levers and materially reduce other expense. All the work that is done on them 20 is on the exterior surfaces. Yet the assembling is very easily performed.

It will be noticed that these levers are arranged in pairs and that the levers of one pair project toward each other from their 25 pivots and have upwardly extending cams 34 with rounded ends which come substantially in contact with each other but never press on each other. They project up above the level of the pivot pins 30 to support a 30 block 35 above them. This block preferably is made of sheet steel bent into shape to provide a flat upper surface on which rests the valve stem 11. It is bent down at the sides to form guides 39 sliding in opposite 35 grooves in the casing. It has a concave lower surface, or rather a surface at the bottom having two reversely slanting walls 36, for receiving between them the two cams 34. These two cams are alike. They support this 40 block 35 at two points a slight distance apart when it is in its lowest position and keep it from wobbling on account of this method of support.

In operation, assuming the parts to start 45 in the position shown at the left in Fig. 1, the turning of the cam 21 raises the plunger 12 on the top of which the lower ends of the cams 34 rest. This turns the levers individually from the position shown at the left 50 to the position shown at the right in that figure. On account of the construction of these levers 31 that has been described they remain in engagement with their pivot pins and are forced to rotate about them, but the 55 plunger 12 forces them up and on account of the change of angle the upper tips of the cams 34 are not only forced upwardly but are forced back away from each other along the inclined surfaces 36. This has a multiplying raising action on the valve stem 11 through the block 35 which supports it and yet there is no wear on the bottom of the 60 valve stem. This block 35 is a separate piece inserted and can be made of hardened steel 65 without any necessary modification of the

valve stem itself so that the wear will come on it and on the cam levers and practically none of it will come on the valve stem and very little on the top of the plunger 12.

The result of this action is to rapidly raise 70 or open the valve when the cam 21 acts to perform this function and to close it also with great rapidity. It has been found in practice that this rapid opening and closing 75 of the valves is a matter of great importance in Ford cars as they are made at the present time. It is impossible to make the cams 21 sharp enough to perform this function with sufficient rapidity and this multiplier has been introduced to overcome this objection. Although shown as applied to a 80 Ford engine it can be introduced in most other kinds with suitable modifications.

Although I have illustrated and described only a single form of the invention I am 85 aware of the fact that modifications can be made therein by any person skilled in the art without departing from the scope of the invention as expressed in the claims. Therefore I do not wish to be limited to all the 90 details of construction herein shown and described but what I do claim is:—

1. A valve lifting device for an internal combustion engine having a valve plunger, 95 said lifting device comprising a sheet metal casing and means for holding it firmly in position in an engine, said casing having side guide grooves and pivot pins across it spaced from the bottom thereof, pairs of pivot levers having semi-circular grooves across their upper surfaces for receiving said pins, each lever having a quadrant at its lower outer end centered at the center of its groove of such a radius as to bear on the bottom of the casing at all times, whereby 100 the turning of said levers on their pins will not result in the disengagement of the levers from the pivot pins on account of the contact of the quadrant with the bottom of the casing, said levers having means for engaging 105 the top of the valve plunger, and means at a distance therefrom guided in said grooves co-operating with said levers for raising the valve stem in alignment with the plunger, whereby the rapidity of downward and upward motion of the valve stem 110 over that of the plunger is increased.

2. A valve lifting device for an internal combustion engine having a valve plunger, 115 said lifting device comprising a pair of parallel pivot pins, pairs of pivot levers having semi-circular grooves across their upper surfaces for receiving said pins, each lever having a quadrant at its lower outer end centered at the center of its groove, a floor 120 spaced below the pins far enough for the quadrants to bear on it throughout the motion of the levers, whereby the turning of said levers on their pins will not result in the disengagement of the levers from the 125

5 pivot pins on account of the contact of the quadrant with the floor, said levers having means for engaging the top of the plunger of the engine, and means at a distance therefrom co-operating with said levers for raising the valve stem in alignment with the plunger.

3. In a valve lifting device of the character described, the combination of a pair of 10 pivot pins in fixed position, a pair of cam levers pivoted on the bottom surface of said pivot pins and extending inwardly therefrom, each cam lever having a cam on the end projecting upwardly from the lever, 15 said cams having adjacent convex surfaces, and a block of hardened steel resting on the upwardly projecting ends of the cams and having a lower surface provided with oppositely slanting walls for receiving the thrust 20 of the ends of said cams, whereby said block will be raised in a vertical direction without

side motion at a rate more rapid than the bottoms of the cams.

4. In a valve lifting device of the character described, the combination of a pair of 25 pivot pins in fixed position, a pair of cam levers pivoted on the bottom surface of said pivot pins and extending inwardly toward each other therefrom, each cam lever having a cam on the end projecting upwardly from 30 the lever, said cams having convex surfaces and a block of hardened steel resting on the upwardly projecting ends of the cam and having a lower surface provided with oppositely slanting walls for receiving the thrust 35 of the ends of said cams, whereby said block will be raised in a vertical direction without side motion.

In testimony whereof I have hereunto affixed my signature.

WRAY FALWELL.
